MEANS FOR SECURING STRUCTURAL BLOCKS IN FRAMES

Samuel Frank Cox, Pittsburgh, Pa., assignor to
 Pittsburgh Plate Glass Company, Allegheny
 County, Pa., a corporation of Pennsylvania

Application February 9, 1938, Serial No. 189,578

6 Claims.

(Cl. 72—42)

The present invention relates to constructions suitable for securing and sealing the edges of frangible building blocks in relatively rigid chases or frames and it has particular relation to means of so securing blocks composed of glass or similar transparent material.

One object of the invention is to provide means for elastically securing glass building blocks and similar structural units in frameworks in such manner as to permit adjustment of the blocks to accommodate stresses and strains exerted in various directions thereupon.

This and other objects will be apparent from consideration of the following specification and claims, together with the drawing pertaining thereto.

One method of mounting building units of the type of hollow glass blocks involves setting the blocks, in edge to edge relation in groups comprising panels, the panels being secured in position in a wall by means of a suitable framework. Usually these frameworks comprise channel irons or the like beams of conventional design between the flanges of which the marginal portions of the outermost building units are disposed.

Glass building blocks are of transparent character and framework, employed as holding means, therefore, is more or less exposed to view and may be unsightly. Accordingly, for this and other reasons it is desirable to reduce the amount of framework required to a minimum, and, therefore, the groups of building units are frequently of extensive area. Large surfaces without backing or supplementary support are exposed to the atmospheric forces, changes of temperature and the like variations. It will also be apparent that the framework itself is subject to relative distortion by changes of temperature, settling of the building and other factors, and as a result the units in the frame are frequently subjected to substantial stresses which may be exerted either perpendicular to or in the plane of the assembly. These strains are so great that rupture of the units or a part thereof may occur.

In order to seal the space between the edges of the blocks at the margins of the panels and the flanges of the framework, and also to permit a certain degree of relative movement of the panel in the frame, the channel customarily is packed with a soft, plastic caulking compound. Such compound will yield under relatively moderate forces but it does not have sufficient resiliency to return the panel of blocks to its initial position when the stress is relieved.

In a wall constructed in accordance with the

provisions of the present invention, these objectionable strains upon the building blocks are minimized or overcome by provision of elastic securing means which coacts with the plastic caulking material for holding the edges of the outermost units of a panel of building blocks in the framework in such manner as to permit resilient yielding and subsequent return of the units with respect to the frame in any direction.

For a better understanding of the invention reference may now be had to the accompanying drawing in which like numerals refer to like parts throughout and in which Figure 1 is a fragmentary cross-sectional view showing one convenient method of securing the marginal proportions of the building blocks in the supporting framework.

Figure 2 is a fragmentary cross-sectional view showing one manner in which the invention may be employed.

Figure 3 is a fragmentary cross-sectional view taken substantially upon the line III—III of Figure 2.

In the form of the invention disclosed in Figure 1, a channel iron or an I beam, which may constitute a part of the framework of a building of any convenient design or may constitute an independent frame for a preformed panel, is formed with a web 5 having marginal flanges 6 which form a chase or channel for the reception of hollow glass blocks or other structural blocks 7. These blocks conveniently comprise two tray-like sections 8 and 9 which are secured together at their margins 11 by fusing or in any other convenient manner. The formation of these blocks does not constitute a part of the present invention.

A pad or cushion 12 of cork, glass wool or other relatively elastic material is disposed between the web 5 and the adjacent margin of the units 7 and the inherent resiliency thereof permits relative yielding between the blocks and the web. However, upon release of the strains between the block and the framework or upon change of the action thereof the cushion accommodates itself to the resultant change in position of the members.

The margins of the building blocks are held against movement with respect to the flanges 6 by means of springs 13 of phosphor bronze, carbon steel or the like, which roughly are of hair-pin-like cross-sectional contour. As shown in the drawing, the ends of the branches 14 of these springs engage the inner surface of flanges 6 while the bend 15 abuts the adjacent face of the unit 7.

For purposes of providing a moisture-proof and

air-tight seal between the flanges 6 and the surfaces of the building blocks a plastic packing 16 which may comprise a conventional caulking compound of soft yielding nature is disposed in 5 position preferably forwardly of the springs 13. This compound adheres to the surfaces of the glass and the metal of the framework and provides a seal; yet by reason of its plastic nature it will yield under the various forces which may be 10 exerted perpendicularly or otherwise to the block or units 7 and will also permit the unit to return to its initial position or otherwise shift its position in the framework under the urge of the springs 13. However, the spring may be reversed, 15 or it may be rotated ninety degrees so that one tip engages the building block while the other tip engages the adjacent flange.

Springs 13 may be in the form of a plurality of spaced units or sections disposed at convenient 20 distances along the flanges 6 or may comprise one or a plurality of channel-like members so disposed as to engage the panel through its length. In the latter construction they will provide walls or dams against which the caulking compound 16 25 will abut, thus obviating the necessity of filling the entire space between the flanges 6 and the adjacent faces of the units 7 with caulking compound. Substantial economy of construction is thus obtained.

30 The form of the invention disclosed in Figures 2 and 3 comprises a channel member 20 having a web 21 and flanges 22 and a pad 23 of glass wool all of which substantially correspond to the elements 5, 6 and 12 disclosed in Figure 1. The margins of hollow blocks 24 corresponding to blocks 35 7 are also disposed between the flanges 22 and the edge walls 26 thereof engage the pad 23.

The faces 21 of these blocks are held in spaced 40 relation with respect to the flanges 22 by means of a sinuous tape or ribbon-like spring 28 running along the edges of the panels and the apexes of the sinuations of which alternately contact with the inner surface of the flanges 12 and the adjacent base of the block 24 resiliently to urge 45 them apart. The mode of operation of this form of the invention is essentially the same as that of the form disclosed in Figure 1. The space about the spring is filled with caulking material 29.

In the constructions herein disclosed, the caulking compound provides a yielding but air and water-tight seal about the edges of the units. The springs reinforce the caulking compound to prevent undue movement of the panels under 5 steady pressure. They also impart resiliency to the assembly so that the panels, upon slight displacement, are urged back to their normal positions.

Although only the preferred forms of the invention have been shown and described, it will be apparent to those skilled in the art that numerous modifications may be made therein without departure from the spirit of the invention or the scope of the appended claims.

15 What I claim is:

1. A wall structure comprising a framework comprising web members having flanges providing channels, a plurality of hollow glass building blocks disposed in the frame to form a filling 20 panel therefor and having the marginal portions thereof disposed between the flanges of the framework and resilient members disposed between the flanges and the adjacent faces of the building blocks.

25 2. A construction as defined in claim 1 in which the resilient members are of spring material.

3. A construction as defined in claim 1 in which the resilient members are of hairpin-like cross-sectional contour and engage at one end with 30 the inner face of the flange and at the other end with the adjacent face of the building blocks.

4. A construction as defined in claim 1 in which the resilient members comprise springs formed of a sinuous spring tape having the apexes of the 35 sinuations thereof alternately engaging the inner face of the flanges and the adjacent face of the building units.

5. A construction as defined in claim 1 in which a seal of plastic material is further disposed between the flanges and the adjacent faces 40 of the building block.

45 6. A construction as defined in claim 1 in which a backing of resilient material is disposed between the outer margin of the building blocks and the inner face of the web of the frame member.

SAMUEL FRANK COX.
